UNITED STATES PATENT OFFICE.

OTTO T. PETERSON, OF MALDEN, AND ERNEST C. LEACH, OF WEST PEABODY, MASSACHUSETTS, ASSIGNORS TO VICTOR SHOE MACHINERY COMPANY, OF LYNN, MASSACHUSETTS, A CORPORATION OF MASSACHUSETTS.

PRESSER-FOOT MECHANISM.

Application filed August 20, 1921. Serial No. 493,950.

To all whom it may concern:

Be it known that we, OTTO T. PETERSON, a citizen of the United States of America, and a resident of Malden, in the county of Middlesex and State of Massachusetts, and ERNEST C. LEACH, a citizen of the United States of America, and a resident of West Peabody, in the county of Essex and State of Massachusetts, have invented certain new and useful Improvements in Presser-Foot Mechanism, of which the following is a specification.

This invention relates to improvements in presser-foot mechanisms for shoe-sewing machines in which provision is made for automatically regulating the length of thread to be drawn from the source of supply in accordance with the various thicknesses of material being operated upon.

The present invention is an improvement upon the invention shown and described in Letters Patent No. 1,357,237 issued to Lawrence E. Johnson, Edward Erickson, and Otto T. Peterson, Nov. 2, 1920.

In the device of the patent above referred to, the presser-foot is secured to a support slidably mounted in a cam-operated lever adapted to be actuated to release the pressure of the presser-foot when the work is being fed.

The slideable support is adapted also to slide transversely of the lever in order to accommodate the presser-foot to varying thicknesses of material.

It is essential that when the support is given this additional movement transversely of the lever, there should be no cramping thereof which would prevent the support from sliding freely and in the invention manufacturing in the patent above referred to, means was provided for accomplishing this object.

The object of the present invention is to provide a means for taking up the wear when the slideable support becomes worn.

The invention further consists of certain novel features of construction and arrangement of parts which will be readily understood by reference to the description of the drawings and to the claims to be hereinafter given.

For the purpose of illustrating the invention, one preferred form thereof is illustrated in the drawings, this form having

been found to give satisfactory and reliable results although it is to be understood that the various instrumentalities of which the invention consists can be variously arranged and organized and the invention is not limited to the precise arrangement and organization of these instrumentalities as herein shown and described, except as required by the scope of the appended claims.

Of the drawings:

Figure 1 represents a vertical section of a portion of a shoe-sewing machine showing the present invention applied thereto.

Figure 2 represents a sectional detail on line 2, 2, on Fig. 1, and

Figure 3 represents a sectional detail on line 3, 3, on Fig. 2. Both Figs. 2 and 3 are drawn to an enlarged scale.

Similar characters indicate like parts throughout the several figures of the drawings.

In the drawings, 10 is a portion of the frame of a shoe sewing-machine in which is revolubly mounted a shaft 11 having a cam disk 12 secured thereto.

Secured upon the frame 10 in the usual manner, is a work support 13 which may be of any well-known construction.

Fixedly secured in the frame 10 is a rod 14 and over this rod extends a thread *t* drawn from any suitable source of supply.

The thread *t* then passes around a pin 15 secured to the thread lock cam lever 16 which is pivoted at 17 and has at its rear end a roller 18 in the cam path 19 formed in one side of the cam disk 12.

The thread *t* passes from the pin 15 over a stationary pin 20 and then through slots in the downwardly extending arms 21 of a forked member or machine-element 22.

The thread *t* passes from one arm 21 to the other arm 21 under a stud or pin 23 projecting horizontally from the side of the forward end of the lever 16.

From the forked member 22 the thread *t* passes through a hole 24 in the movable frame 25 to the usual wax-pot of a sewing machine.

The cam disk 12 is provided on its outer face with a cam path 26 in which is positioned a roller 27 mounted on the end of the lever or guide-member 28 pivoted at 29, and provided at its outer end with a transverse

groove 30 in which is mounted the slideable forked member 22 having rack teeth 31 formed in one edge thereof.

The pivot 29 is provided with a gear 32 on its inner end, the teeth of which mesh with the rack teeth 31 of the slideable member 22.

The plate 33 secured to the end of the lever 28 prevents the displacement of the member 22.

10 This rack member 22 is provided with a forwardly extending arm 34 having adjustably secured to the outer end thereof, the presser-foot 35.

15 The arm 34 has a shoulder 36 formed thereon coacting with the upper face of the lever 28 to limit the downward movement of said member 22. The member 22 is also provided with an upward extension 37 between the upper end of which and the lever 28, is

20 a helical spring 38 which tends to retain the presser-foot 35 in its normal position and against the tension of which said presser-foot is adapted to be lifted.

Secured to the pivot 29 is an arm 39 adapted to be manually operated to adjust the presser-foot 35 relatively to the lever 28 and to accommodate it to varying thicknesses of material.

25 This is accomplished by the operator moving the arm 39 and thereby turning the pinion 32, raising and lowering the presser-foot 35 at will.

When any work is placed upon the support 13, the operator adjusts the presser-foot 35 in the manner just referred to so that it will press upon the upper face of the work, after which it will be automatically adjusted as the material varies in thickness.

30 Owing to the fact that the slideable member 22 is located outside of the pinion 32 and between it and one of the guide walls of the transverse groove 30 formed in the lever 28, any movement imparted to said lever 28 by the cam path 26, will be transmitted to the presser-foot 35 thereby removing it from the work when it is desired to feed the latter, or exerting a gripping pressure when the work has been fed.

35 The main portion of the cam path 26 retains the operating face of the presser-foot 35 in contact with the work on the support 13 and causes it to exert a gripping pressure thereon, but when it is desired to move the work along the support, the roller 27 of the lever 28 moves into the portion 40 of the cam path 26 thereby causing the presser-foot to be lifted from the work temporarily while the work is being moved into a new position.

40 When the presser-foot is moved downwardly by the cam-controlled lever 28, the work will be securely gripped thereby against the support 13, the lower face of the presser-foot 35 being forced into the face of the work by the cam 12.

The machine is so built that the member 22 will be cramped between the opposite walls of the transverse guide groove 30 when the lever 28 is moved about its pivot 29. Just prior to the roll 27 entering the throw 40 to 70 release the gripping pressure upon the work, the pinion 32 is locked to prevent any sliding movement of the member 22.

Consequently, when the roller 27 enters the throw 40, the presser-foot 35 will be 75 lifted bodily from the work and will remain free from contact therewith until the completion of the feeding operation when it will be released and the spring 38 will be permitted to return the presser-foot into 80 light contact with the work before the roll 27 enters the concentric portion of the cam 26 to produce the gripping pressure upon the work.

85 It is obvious that when the slideable member 22 is moved transversely of the outer end of the lever 28, the lower operating face of the presser-foot 35 will remain constantly in parallelism, in whatever position said presser-foot may be, relative to the lever 28 90 and when the lever 28 is in position to grip the work, said operating face is constantly in parallelism with the work support 13 regardless of the thickness of the material being acted upon.

95 This operating face of the presser-foot will only assume a position at an angle to the work support 13 when the presser-foot is lifted by the action of the throw 40 upon the roller 27 at the rear of the lever 28 to 100 permit the work to be fed. At all times when the roller 27 is in the concentric portion of the cam path 26, the operating face of the presser-foot 35 is parallel with the face of the work support 13 and this is true 105 regardless of the position of said presser-foot 35 relative to the lever 28 at this time.

When the throw 40 operates the lever 28, the operating face of the presser-foot 35 will be removed entirely from the work and 110 held in this position until the work has been fed, after which the operating face will be returned into light contact with the work by means of the spring 38, the tension of which is only sufficient to position said presser-foot 35 without exerting any gripping pressure upon the work.

When the machine is in operation, the shoulders 36 of the member 22 will be separated from the upper face of the lever 28 120 and the operating face of the presser-foot 35 will be held by the spring 38 in light contact with the work until the first stitch has been formed. When the lever 28 is moved about its pivot by the throw 40, the 125 presser-foot 35 will be lifted free from contact with the work and will be held in elevated position until the work has been fed. At the conclusion of the work-feeding operation, the spring 38 will force the operating 130

face of the presser-foot 35 into light contact with the work, this action occurring while the roll 27 is still in the throw 40. As the roll 27 moves into the concentric portion of the cam 26, the operating face of the presser-foot 35 will be forced into the material and a gripping pressure exerted thereon.

When the cam 26 acts on the left end of the lever 28 this lever will be moved about its pivot 29 and carry the members 22 and 35 therewith, the presser-foot 35 being caused thereby to give a gripping pressure upon the work on the support 13. This action is due largely to the location of the pivot 29 adjacent to the sliding member 22 so that when said lever 28 is moved about its pivot while the presser-foot 35 is in contact with the work, the slide 22 will be cramped between the walls of the transverse groove 30 on the lever 28 and by this cramping operation said slide will be prevented from moving transversely of the lever 28.

Consequently, when the left hand end of the lever is moved upwardly by the cam 26, the operating face of the presser-foot 35 will be forced into the yielding material upon the work support 13 and firmly grip the same.

While the work is gripped in this manner, the needle enters the material and a stitch is formed. Subsequently, while the work is still gripped, the awl is moved to the right and then pierces the material. While the awl is still in the material the roller 27 will enter the throw 40 and cause the gripping pressure of the presser-foot to be released, and the operating face thereof will be lifted from the work preparatory to another feeding of the same, this feeding being accomplished by the movement of the awl to the left.

The pin 23 is adapted to move in the forked end of the member 22, said pin being moved by the action of the cam path 19 on the lever 16 in the end of which said pin is mounted.

The cam path 19 is provided with a throw adapted to oscillate the lever 16 at the proper time to measure off the given quantity of thread for the stitch, the pin in doing this moving longitudinally of the slot in the end of the member 22.

As the thread *t* in crossing this slot passes beneath the pin 23, it is obvious that if the slideable member 22 was always in the same position, a given length of thread would always be measured by the oscillation of the lever 16 and the movement of the pin 23.

It is desired, however, to measure off different lengths of thread for different thicknesses of material and this is readily accomplished by means of the slideable member 22, it being self-evident that when the presser-foot 35 is raised the thread-carrying

passages in the arms 21 of the member 22, are similarly raised to a new position corresponding with the thickness of the material and when in this raised position a greater quantity of thread will be drawn from the source of supply by the movement of the pin 23 in the forked end of the member 22, the lowermost position of said pin being the same under all conditions.

It is obvious that this thread measuring device will operate after the presser-foot 35 has returned into contact with the work. When the takeup device is operating, the pin 23 will be in its highest position and the pin 15 will be in position to coat with the pin 20 to lock the thread to prevent it from being fed from the source of supply.

The roller 18 is of less diameter than the width of the cam path 19 and is in contact with the inner wall of said path only when the lever 16 is being moved about its pivot to measure the thread. The roller 18 never contacts with the opposite wall of said path. The pivot member 17 has secured to its outer end an arm 17^a to the end of which is secured a spring 17^b, the opposite end of which is fastened to the framework of the machine, all as described in the Letters Patent No. 1,133,149, issued Mar. 23, 1915, to L. E. Johnson and Edward Erickson.

This spring retains the pin 15 in contact with the pin 20 except during the thread measuring operation.

When the pins 15 and 20 are in contact, the roller 18 is in contact with neither wall of the cam path 19. When in the rotation of the cam 12, the throw of the cam path 19 comes into contact with the roller 18, the lever 16 will be moved about the pivot 17 and the pins 15, 20 will be separated. When the roller 18 again enters the concentric portion of cam path 19 it will be in position free from either wall of said cam paths being retained in this position by the spring 17^b holding the pins 15, 20 in contact.

Mounted upon the fixed rod 14 is a split block 41 having a clamping bolt 42 mounted therein by which said block 41 may be securely clamped in adjusted position about the axis of said rod 14. This block 41 has upwardly extending ears 43 in which is mounted a stud 44 forming a pivot for a stop member 45.

This stop member 45 has its forward lower end in contact with the upper face of the block 41 thereby preventing forward movement of said member 45 about the axis of the pivot 44.

The rear end of the stop member 45 is separated from the upper face of the block 41 as shown in Fig. 1 of the drawings, and said member 45 is normally retained in the position indicated in said Fig. 1 by means of the spring 48 disposed within a socket 130

in the block 41 and bearing against the under edge of the member 45.

When the roller 27 is in the concentric portion of the cam path 26 and the presser-foot 35 is in gripping contact with the work, the upper extension 37 of the member 22 is removed from the revoluble wheel abutment 47 as indicated in Fig. 1 of the drawings.

10 When the roller 27 enters the throw 40 of the cam path 26 and the presser-foot 35 is lifted from the work, the upward extension 37 of the slidable member 22 will come into contact with the revoluble wheel abutment 47 and further rear movement of said extension 37 is prevented.

As a result of this construction, the slid-
able member 22 may be crimped between
the opposite walls of the transverse groove
20 30 when it is desired to move the presser-
foot 35 by the oscillation of the lever 28 but when it is desired to effect the sliding movement of the member 22 relatively to the lever 28, the cramping of the member 22
25 against the opposite walls of the transverse groove 30 is prevented by the contact of the upward extensions 37 with the revoluble abutment 47.

It is obvious from an inspection of the
30 drawings that this abutment is slightly
yielding against the tension of the spring 48
and the entire block 41 with the stop member
45 and revoluble abutment 47 thereon may
be adjusted about the axis of the fixed rod
35 14 to vary the position of said abutment
relatively to the extension 37.

In other words, the cramping of the presser-foot support in its operating lever is permitted when such cramping is desired in the operation of the machine and is prevented when in the operation it is desirable to have said presser-foot support freely slide transversely of its operating lever.

It is self-evident that by adjusting the
45 block 41 on the rod 14, the revoluble abut-
ment 47 may be positioned so that the side
walls of the slidable member 22 will be in
perfect parallelism with the opposite walls
50 of the transverse groove 30 of lever 28 when
the operation of the machine requires the
member 22 to be adjusted transversely of
the operating lever 28.

The constant sliding of the member 22, during
55 the operation of the machine, causes the
same to become worn and if some provision
is not made to take up the wear, the
effectiveness of operation would be greatly
affected and poor results attained.

In order to meet this objection, one wall
60 of the member 22 is inclined, as at 50, and
one wall of the groove 30 is also inclined
and formed on a separate block 51, the inner
end of which is normally separated from the
face 52 of the lever 28.

The plate 33 is also normally separated 65
from the face 53 of the member 22 which is
secured to the lever 28 by the screws 54 and
the screw or adjusting member 55.

That portion 56 of the screw 55 between
its head 57 and its threaded shank 58, is 70
eccentric and positioned in a cylindrical
hole in the block or adjustable track-mem-
ber 51.

The threaded shank 58 has mounted
thereon the adjusting nut 59. 75

As the sliding member 22 wears, the
screw 55 may be turned about its axis there-
by causing the block 51 to be moved to-
ward the slide 22 and into contact with the
inclined face 50 thereof. 80

When this adjustment has been made, the
nut 59 is turned on the shank 58 until the
eccentric portion 56 is locked in its ad-
justed position.

This clamping of the nut 59 will cause the
screw 55 to be moved endwise causing the
contacting inclined faces of the slide 22 and
block 51 to move the slide transversely so
that its face 60 will contact with the rear
wall of the groove 30 in the lever 28. 85 90

By means of these two adjustments the
slide 22 is always provided with guide walls
which will insure its travel in a straight
line no matter how much it may wear.

This is of great importance as without
this provision for taking up the wear of the
slide 22 it would be liable to wobble and the
presser-foot mechanism would soon become
inoperable or at least work so imperfectly
that a new slide would be necessary. 95 100

With the construction herein shown and
described the same slide 22 may be used
indefinitely by simply making the proper
adjustments.

It is believed that the operation and many
advantages of the invention will be under-
stood readily without further description.

Having thus described our invention, we
claim—

The combination of a guide-member in-
cluding an aperture and a plane guide-wall,
a second guide-wall at an angle to the first
said guide-wall, a machine-element mounted
against said guide-walls for longitudinal
sliding movement, an adjustable track-
member provided with a plane guide-wall
at an incline to the other said guide-walls
and against said machine-element so as to
prevent outward movement and rotary
movement of the said machine-element
while permitting said longitudinal sliding
movement, said adjustable track member
having a cylindrical hole therethrough, and
an adjusting member rotatably fitted in the
aperture of the first said track-member and
provided with an eccentric part fitted in
said cylindrical hole for moving said ad-
justable track-member towards the second 110 115 120 125

said guide-wall, means being provided on
said adjusting member for moving said ad-
justable track-member towards the first said
guide-wall, means being provided to secure
said adjusting member in its different ad-
justments.

Signed by us at 746 Old South Bldg.,

Boston, Mass., this 19th day of August,
1921.
